ALBERT N. WOODRUFF, OF WASHINGTON, DISTRICT OF COLUMBIA.

TYPE-BAR MECHANISM.

Application filed May 11, 1926. Serial No. 108,308.

My present invention relates generally to typewriters and more particularly to type bar mechanisms or actions of the general type described and claimed in my copending application Serial No. 91,511, which was filed March 1, 1926, and which includes a mechanism in which the type bar is pivotally supported at one end and provided with teeth forming a gear surface adjacent to said pivot, a sub-lever being pivotally mounted at one end and having an angularly disposed gear surface at its opposite end engaging the gear surface of the type bar and the sub-lever in turn having a portion adjacent to its pivoted end engaged in movable relation by a part of the key lever inwardly or rearwardly beyond the intermediate fulcrum of the latter. According to this construction the sub-lever was arranged in an approximately upright position and the initial strain at the start of movement of the parts necessarily resolved itself upon the gear teeth connecting the sub-lever with the key lever.

A primary object of my present arrangement is to re-arrange the parts in such manner as to reduce to a material extent the vertical dimension necessary for their support and operation, and a further object is to relieve the connecting gear teeth of the type bar and sub-lever of all strain at the start of operation.

A still further object of my present arrangement and construction is to obtain additional benefits in so far as simplicity, strength and durability are concerned and at the same time retain all of the operating advantages of my former construction above outlined.

In the accompanying drawing which illustrates my present invention and forms a part of this specification:—

Figure 1 is a vertical longitudinal section illustrating my invention, and,

Figure 2 is a detail perspective view of the type bar sub-lever and key lever removed and in their normal relation.

Referring now to these figures, my invention proposes a type bar action including a type bar 10, which may have adjacent to its free end a series of lengthwise spaced type members 11, and which has adjacent to its opposite end a pivot opening 12, and a laterally enlarged portion 13. The type bar 10 is flat throughout as plainly to be seen in Fig. 2, and its opening 12 at its inner or

rear end adapts the same to pivotal mounting upon a type bar supporting rod 14. Along the lower face of its laterally enlarged portion 13, the type bar has gear teeth 15 which form a geared surface eccentric with respect to the pivot opening 12, and it will be noted in Figs. 1 and 2, that in the normal position of the parts the type bar 10 extends forwardly from the supporting rod 14 in an approximately horizontal position with its free or type carrying end resting for instance upon a type bar rest pad 16.

Below the free or type carrying end of the type bar 10 and rearwardly of the type bar rest pad 16, the sub-lever 17 is pivoted at its forward end upon a supporting cross rod or bar 18. This sub-lever 17 in accordance with my present invention normally extends rearwardly in a substantially horizontal position beneath the type bar 10, and has its substantially widened rear end provided with a curved gear surface 19 for engagement with the gear surface 15 of the type bar, it being noted that the upper edge of the inner end of the sub-lever 17 rests in the normal position of the parts against the lower surface of the type bar 10, whereby upon initial upward pressure against the sub-lever 17 the latter directly engages the type bar so as to elevate the latter without strain upon the intermeshing gear teeth 15 and 19.

Upon its lower edge and intermediate its ends the sub-lever 17 has a rounded projection 20, which is engaged as shown by the upper flat surface 21, at the inner or rear end of the key lever 22, which is fulcrumed intermediate its ends upon a supporting cross bar or rod 23, and which is provided at its forward end with a finger piece or key 24.

Thus when the key 24 or finger piece of the key lever 22 is initially depressed, the forward portion of the key lever will be moved downwardly, and that portion thereof rearwardly of its fulcrum 23 will be shifted upwardly so that the upwardly presented flat surface 21 at its inner end will, by virtue of its engagement with the rounded projection 20 of the sub-lever 17, shift this sub-lever upwardly upon its pivot 18, causing the type bar 10 to swing upwardly and rearwardly on its pivot 12.

It is to be noted that during this movement the surface 21 slides relative to the projec-

tion 20, and thus the point of engagement between the key lever 22 and the sub-lever 17 constantly shifts in a direction toward the pivot 18 of the sub-lever. Also in view of the eccentricity of the geared surface 15 of the type bar 10 with respect to its pivot 14 it is obvious that during the swinging movement of the type bar the point of engagement between the type bar and the sub-lever 10 constantly shifts toward the pivot 14 of the type bar.

From the foregoing it is plain that at the start of movement, the parts are in position to develop maximum power, as compared to the finish of the movement, where power is sacrificed to speed, since speed is desired at the finish of the movement, while on the other hand power is necessary at the start of movement.

20 During the initial portion of its swinging movement the type bar 10 raises while the latter portion of its movement is a falling movement, during which little, if any, power is required.

25 After action, the parts are returned to their normal position upon release of the key lever 22 by virtue of a spring 25, one end of which is anchored in any suitable manner within the frame 26 of a typewriting machine, and the other end of which may be attached in any suitable manner to the sub-lever 17.

I have in the present instance shown a type bar 10, provided with type at lengthwise spaced points adjacent to its free end as at 11, and while it is to be understood that this arrangement is intended to operate in practice in connection with a platen 27 shiftable between the full and dotted line positions of Fig. 1, to permit of proper engagement of the several type, this movable platen and the means for moving the same form no part of my present invention and will be included in a separate application.

45 I claim:

1. In a typewriter, a type bar pivotally supported adjacent to one end and to normally extend forwardly in a substantially horizontal position and having at its rear pivoted end a lateral enlargement provided with lower teeth forming a curved gear surface along a line eccentric with respect to its pivot, a sub-lever pivotally mounted at its forward end and normally extending in a

substantially horizontal position beneath the type bar with the upper portion of its rear end engaging the type bar adjacent to the pivoted end of the latter, said rear end of the sub-lever having a curved gear surface cooperating with the gear surface of the type bar, and said sub-lever having a lower rounded projection intermediate its ends and a key lever fulcrumed intermediate its ends and having its inner end provided with an upwardly facing engaging surface in contact with the rounded projection of the sub-lever, as described.

2. In a typewriter, a horizontally disposed type bar pivotally supported adjacent to one end and having an eccentric gear surface adjacent to its pivot, a sub-lever pivotally supported at its forward end horizontally below and in engagement with the type bar and having a gear surface at its rear end engaging the geared surface of the type bar, and a key lever fulcrumed intermediate its ends below and forwardly of the sub-lever and having its rear end in engagement with the lower surface of the sub-lever and shiftable in its effective movement toward the pivot of the said lever.

3. In a typewriter, a type bar, sub-lever and key lever all normally disposed in horizontal positions, the key lever having a portion engaging the sub-lever, and shiftable in the effective movement of the parts toward the pivot of the sub-lever, and the sub-lever and the type bar having intermeshing teeth arranged to shift the engaging point of the sub-lever toward the pivot of the type bar during effective movement of the parts.

4. In a typewriter, a type bar, sub-lever and key lever all normally disposed in horizontal positions, the type bar and sub-lever being pivotally supported in superposed relation and at relatively opposite ends, said sub-lever normally engaging the type bar at a point intermediate the ends of the latter, and said sub-lever and said type bar having intermeshing gear teeth, the teeth of the type bar being disposed eccentric to the pivot thereof and the key lever being fulcrumed intermediate its ends and having its inner end in sliding contact with the sub-lever and shiftable in the effective movement of the parts toward the pivot of the said lever.
